Co., Cleveland, Ohio, a corporation of Ohio

Application November 12, 1948, Serial No. 59,654

20 Claims. (Cl. 238—292)

1

This invention relates to a rail brace such as is applied to a railroad rail to resist any tendency of the rail to overturn outwardly from the center of the track and to clamp it to the tie plate, base plate or switch plate on which it rests, thus holding the rail against movements relative to the plate, which latter, in turn, is secured to a supporting tie as is well understood in the art.

Rail braces of the type contemplated by this invention are most frequently applied against the stock rails alongside split switch points but their use is not necessarily limited to such application.

Further, braces of this type are frequently made adjustable to compensate for variations in the dimensions of the rail, the seat for the rail and brace, in the brace itself, and also to afford a means of retightening the assembly after wear takes place.

Rail braces employed for this purpose generally have a portion which engages one of the sloping base flanges of the rail and the vertical web of the rail where it merges with the base flanges and a portion which engages the web beneath the rail head. Difficulty has been experienced with the rail braces in use, in that the braces tend when in track to work downwardly of the sloping base flanges of the rails and away from the webs of the rails until the braces do not effectively clamp the rails to the base plates or brace the rails against tilting or moving away from the shoulders of the base plates. This difficulty has been accentuated by the use of vertical hold-down or clamping bolts for securing the braces to the base plates in rail clamping and bracing position.

Various arrangements have been employed to overcome this tendency of the rail braces to work away from the rails as, for instance, it has been usual to employ wedge members inserted between the rail braces and fixed abutment or back stops secured to the base plates, the function of the wedges being to force the braces toward the rails. However, such wedge members have not been entirely satisfactory for the purpose since there is a tendency for the wedges to work toward loosened position due to wear occurring between the parts of the brace and wedge and to the vibratory, jarring and other forces set up by the passage of trains along the rails.

An object of the present invention is to provide a rail brace which is so constructed that when installed the brace is at all times and under trackage conditions held in tight and effective

2

rail clamping and bracing position, thus insuring adequate, safe and effective maintenance of the necessary clamping and bracing relationship between the brace and the rail.

5 Another object is to provide a rail brace construction employing a wedge to maintain the brace in proper rail bracing and clamping relationship and wherein the wedge member under the vibratory, jarring and other forces occasioned by trains passing along the rail tends at all times to move automatically into tight wedging position thereby maintaining the brace in the proper clamping and bracing position and compensating for wear which may occur between the parts.

10 A further object is to provide a rail brace construction as defined in the last object and wherein it is not necessary when installing the rail brace to drive the wedge member into operative position since said member automatically will move into tight wedging position under the action of trains passing along the rail.

15 A still further object is to provide a rail brace construction such as defined in the last two mentioned objects and wherein, in combination with the self-tightening wedge member, a hold-down bolt arrangement is employed which acts at all times and under trackage conditions to urge the rail brace toward the rail rather than away from the rail, thus doubly insuring the maintenance of the necessary clamping and bracing relationship between the brace and the rail.

20 Further and additional objects and advantages will become apparent hereinafter during the detailed description of an embodiment of the invention which is to follow.

The invention contemplates a self-tightening rail brace wherein the self-tightening action is obtained by a novel wedge construction that is automatically self-tightening under trackage conditions or is obtained by said wedge construction acting in combination with a hold-down bolt arrangement which tends at all times to urge the rail brace toward the rail and into proper rail clamping and bracing position.

25 Rail braces employing the usual vertically acting hold-down bolts may be rendered self-tightening in use by means of the novel self-tightening wedge that urges the brace toward and maintains the same in proper relative clamping and bracing position with respect to the rail.

The novel wedge and the parts of the rail brace that coact therewith are so constructed that 30 when the brace is in trackage the vibrations,

shocks, jars and other forces to which the brace is subjected by the passage of trains along the rail automatically produces movement of the wedge in the tightening direction, wherefore the wedge maintains the brace in proper relative clamping and bracing position, notwithstanding the occurrence of wear in the parts of the brace.

In addition, the invention contemplates, as a further aspect thereof, the use of the novel wedge construction in combination with a hold-down bolt arrangement such that the hold-down bolts not only exert a vertical clamping force but also produce a horizontal force on the brace overcoming the tendency of the brace to move downwardly of the sloping base flange of the rail and tending to move the brace upwardly of said sloping base flange of the rail and toward the web of the rail.

Referring to the accompanying drawing illustrating embodiments of the invention,

Fig. 1 is a partial sectional and partial elevational view illustrating one form of rail brace construction embodying the invention, the rail being shown in transverse vertical section, the rail brace in longitudinal vertical section with the wedge member in end elevation, and the base plate on which the rail is mounted being shown in longitudinal side elevation.

Fig. 2 is partial plan and partial sectional view of the rail, rail brace and base plate shown in Fig. 1, with the head of the rail omitted and the web thereof shown in horizontal section and with the clamp plate of the rail brace omitted and the brace and wedge shown in plan, said Fig. 2 being taken looking at Fig. 1 substantially along the line 2-2 of Fig. 1.

Fig. 3 is an elevational view of the rail brace with the clamping nuts and washers omitted from the hold-down bolts, and with the base plate shown as secured to a tie, said view being taken looking from the right hand side of Fig. 1.

Fig. 4 is a detached detail top plan view of the wedge member shown in Figs. 1 to 3.

Fig. 5 is a longitudinal side elevational view of said wedge member.

Figs. 6, 7 and 8 are views similar to Figs. 1 to 3 inclusive but illustrating a modified form of construction embodying the invention.

Fig. 9 is a top plan view of the two separate wedge members employed in the modified construction of Figs. 6 to 8 inclusive, and

Fig. 10 is a longitudinal side elevational view of the wedge members shown in Fig. 9.

The novel wedge member embodying the invention is illustrated as employed in a rail brace in combination with a hold-down bolt arrangement such that the latter tends at all times to urge the rail brace toward the rail and into proper rail clamping and bracing position. It will be understood, however, that insofar as the wedge aspect of the invention is concerned, the novel wedge may be usefully employed in a rail brace of ordinary construction wherein the hold-down bolts exert merely vertical clamping forces on the rail brace.

Referring to the construction shown in Figs. 1 to 5 inclusive, a railroad rail is indicated generally at 11 and said rail comprises a base formed of the base flanges 12 having downwardly sloping upper surfaces 13. The rail further includes a vertical web 14 which at its lower end is integral with and merges into the base while at its upper end it is integral with and merges into the rail head 15. The construction of the rail is conventional.

The rail 11 is shown as mounted in a recess formed in the upper side of a base plate 16 which base plate is secured to the top of a cross tie 17 in a manner well understood in the art (see Fig. 3). The rail 11 is held against the left hand shoulder of the recess in the upper side of the base plate as viewed in Fig. 1 while a fixed abutment of back stop member 18 is secured by rivets or other suitable means in the recess and against the right hand shoulder thereof. The fixed abutment or back stop member 18 is shown as in the form of a rectangular block having a longitudinal straight side contacting the right hand shoulder of the recess in the upper side of the base plate and a similar longitudinal straight side located adjacent to but spaced from the rail brace. The construction thus far set forth is conventional and well understood.

The rail brace comprises a block B having a vertical portion 19 which when the brace is in position extends longitudinally of the rail adjacent to the web thereof and is provided adjacent its upper end with a web engaging portion 20, it being noted that clearance exists between the upper end surface of the portion 20 and the underside of the rail head 15 so that the portion 20 exerts horizontal thrust against the web of the rail without any upward thrust on the underside of the rail head 15 that would tend to tilt the rail.

The vertical portion 19 below the web engaging portion 20 is spaced from the web 14 and at its lower end is integral with and merges into an intermediate portion 21 which has on its underside a curved surface complementary to the merging radius between the web 14 and the downwardly sloping surface 13 of the base flange 12 of the rail and a downwardly inclined surface which engages the downwardly inclined upper surface 13 of the right hand rail base flange 12.

The rail brace further includes a downwardly inclined portion 22 which is integral with the intermediate portion 21 and has its underside spaced from the downwardly sloping upper surface of the right hand rail brace flange 12 and from the upper surface of the base plate 16. The portion 22 at its outer end is provided on its underside with a rib 23 extending transversely of the rail brace and of the base plate 16 and bearing upon the base plate within the recess and to the left of the back stop 18 as viewed in Fig. 1.

The right hand or free end of the portion 22 is formed in the present instance with two inclined parallel wedging surfaces 24 and 25 that extend in a direction transversely of the base plate and are separated intermediate the longitudinal sides of the rail brace by a recess 26. The purpose of the inclined surfaces 24 and 25 and the recess 26 will be explained in greater detail hereinafter.

The portion 22 of the rail brace adjacent its junction with the intermediate portion 21 and on the upper side of the portion 22 is provided with a downwardly inclined surface 27 that is shown as angularly disposed with respect to the downwardly sloping upper surface 13 of the base flange 12 of the rail, it being noted that the surface 27 is somewhat more steeply downwardly inclined than is the surface 13 of the rail. The portion 22 of the rail brace intermediate the rib 23 and its point of joinder with the intermediate portion 21 is provided with spaced openings 28 which are elongated in a direction toward the web of the rail or longitudinally of the rail brace.

The openings 28 are spaced apart transversely

of the rail brace or longitudinally of the rail and accommodate the shanks 29 of the hold-down bolts later to be referred to, it being understood that the elongation of the openings 28 is for the purpose of providing adjustment for the rail brace toward and from the web of the rail and to facilitate the installation of the brace.

The hold-down bolts have their shanks 29 disposed at an angle to the vertical and substantially perpendicular to the downwardly sloping upper surface 13 of the rail brace flange 12. The shanks 29 of the hold-down bolts at their lower ends are provided with integral vertically extending short portions that have integrally formed on their lower ends bolt heads 30, said short vertical portions of the hold-down bolts being located in vertical openings 31 in the base plate 16 and which openings 31 terminate in recesses on the underside of the base plate 16 and in which recesses the bolt heads 30 are located flush with said underside of the base plate. The shanks 29 of the hold-down bolts are of such length as to extend well above the upper side of the portion 22 of the rail brace and have their upper ends threaded as indicated at 32 to receive thereon-heavy spring washers 33 and cap nuts 34.

A clamping plate 35 provided with openings through which the hold-down bolt shanks 29 project with suitable clearance is interposed between the portion 22 and the heavy spring washers 33.

The clamp plate 35 adjacent its left hand end as viewed in Fig. 1 is provided on its underside with a downwardly inclined surface adapted to bear upon and complementary to the downwardly inclined surface 27 of the portion 22. The underside of the clamp plate 35 to the right of the downwardly inclined surface that engages said surface 27 is spaced from the upper surface of the portion 22 and it will be noted that the clamp plate 35 extends beyond the free end of the portion 22 and terminates closely adjacent to the left hand side of the fixed abutment member 18; that is, the clamp plate 35 is provided with a lip portion which overlies the space between the end of the portion 22 of the rail brace and the fixed abutment member 18. The underside of this lip portion of the clamp plate 35 is provided with parallel upwardly inclined surfaces 36 and 37 (looking from left to right of Fig. 3) with said surfaces separated by an intermediate recess 38.

The block B is provided with longitudinal side walls 39 which are integral with the portions 19, 20, 21 and 22 and extend from the portion 20 to the free end of the portion 22, with the upper surfaces of the side walls being formed with a slight concave curvature.

A wedge member indicated generally at 40 is mounted in the recess of the base plate 16 intermediate the free end of the portion 22 of the block B and the fixed abutment member 18 and underlying the lip portion of the clamp plate 35. The wedge 40 is provided with a straight side surface 41 that reacts against the longitudinal straight side of the fixed abutment 18 that is adjacent to but spaced from the rail brace. The opposite longitudinal side of the wedge 40 is shown as comprising two parallel inclined wedging surfaces 42 and 43 spaced apart intermediate the ends of the wedge by a space indicated at 44. The wedging surfaces 42 and 43 coact with the wedging surfaces 25 and 24, respectively, on the end of the portion 22 of the block B and as the wedge moves in the direction indicated by the arrow A in Fig. 2 it forces the block B toward the web of

the rail and upwardly of the downwardly sloping surface 13 of the base flange 12 of the rail as will be well understood.

It will be noted that a shoulder 43a is provided at the high end of the wedge surface 43 and that said shoulder is located in the recess 26 in the free end of the block portion 22, wherefore, should the wedge work in a direction opposite to that indicated by the arrow A, said shoulder 43a would positively engage the lower end of the recess 26 (as viewed in Fig. 2) and thus arrest further movement of the wedge 40 in the loosening direction, thereby assuring against complete displacement of the wedge from its operative position beneath the lip of the clamp plate 35.

The upper surface 45 of the wedge 40 is provided with upwardly inclined (looking from left to right of Fig. 5) wedge portions 46 and 47 that have their wedging surfaces parallel to each other and the portions 46 and 47 are separated intermediate the ends of the wedge 40 as clearly indicated in Figs. 4 and 5.

The wedge portions 46 and 47 cooperate with the upwardly inclined surfaces 36 and 37, respectively, on the underside of the lip of the clamp plate 35 to effect the self-tightening action of the wedge as will more fully be explained hereinafter.

Assuming that the rail 11 is positioned in the recess of the base plate 16 as shown in Fig. 1 and that the block B is mounted in position against the rail, also as indicated in Fig. 1, with the inclined shank portions 29 of the hold-down bolts extending through the openings 28 and with the wedge member 40 positioned intermediate the free end of the portion 22 of the block B and the fixed abutment member 18, it will be noted that the wedging surfaces 42 and 43 of the wedge member engage the surfaces 25 and 24 on the free end of the block and may act to urge the block toward the rail. The clamp plate 35 is then positioned on the block B with the shanks 29 of the hold-down bolts extending through the openings in the clamp plate and with the downwardly inclined surface on the underside of the left hand end of the clamp plate bearing against the downwardly inclined surface 27 of the portion 22 of the block. At this time the lip of the clamp plate 35 will overlie the wedge 40 and the inclined surfaces 36 and 37 on the underside of the lip will bear against the wedging surfaces of the wedge portions 46 and 47 on the upper side of the wedge. The heavy spring washers 33 and the cap nuts 34 are now positioned on the hold-down bolts with said washers bearing against the upper side of the clamp plate 35, wherefore when the cap nuts 34 are screwed downwardly on the bolts the hold-down forces of the bolts and nuts act through the washers 33 upon the clamp plate 35. The hold-down forces acting through the inclined surface 27 of the portion 22 of the block B results not only in a vertical hold-down or clamping action but also in a horizontal clamping action which tends to force and maintain the block B tightly against the rail in proper clamping and bracing relationship thereto, with the left hand base flange of the rail as viewed in Fig. 1 held firmly against the left hand shoulder of the recess in the base plate. This horizontal hold-down force tends to cause the intermediate portion 21 of the block B at all times to ride upwardly of the downwardly sloping surface 13 of the right hand rail base flange 12 and obviates any tendency of the portion 21 to work downwardly of the surface 13. Therefore, the arrangement described

with respect to the hold-down bolts and the manner in which the hold-down force thereof is exerted on the block B results in a self-tightening action on the rail brace at all times that maintains the brace in proper clamping and bracing position relative to the rail, notwithstanding vibrations, jars, shocks and wear to which the brace may be subjected in use, it being observed that the hold-down force is transmitted through the heavy spring washers 33.

Furthermore the hold-down forces on the clamp plate 35 causes the surfaces 36 and 37 on the underside of the lip of the clamp plate to react on the wedging surfaces of the wedge portions 46 and 47 on the upper side of the wedge 40 and such reaction produces a resultant force tending to move the wedge at all times in the direction of the arrow A of Fig. 2, that is in a direction that tightens the wedging surfaces 42 and 43 of the wedge with respect to their coacting wedging surfaces 25 and 24 and thus enable the wedge 40 to effectively and fully operate to maintain the block B in proper rail bracing position wherein the rail is held against the left hand shoulder of the recess in the base plate.

In actual practice it has been found not necessary in installing the rail brace to drive the wedge 40 tightly home since the wedge is self-tightening. It has been found that under the vibration, shocks and jars of a train passing along the rail the reaction of the surfaces 36 and 37 on the underside of the lip of the clamp plate 35 against the wedging surfaces of the wedge portions 46 and 47 of the wedge actually causes the wedge automatically to move in the direction of the arrow A of Fig. 2 and thus the wedge is self-tightening.

In the event of wear taking place between the parts of the rail brace, the wedge will not work loose due to the self-tightening characteristics referred to but, on the contrary, will become tighter and tighter under train vibrations, it being recalled that the hold-down force acting on the clamp plate 35 is transmitted through the heavy spring washers 33 and therefore the inclined surfaces on the underside of the lip of the clamp plate react on the wedge surfaces of the portions 46 and 47 of the wedge to cause the latter to travel in a self-tightening direction.

It will be understood that in place of two wedging surfaces 42 and 43 the wedge may be provided with a greater number of such wedging surfaces or with a single wedging surface and that the cooperating surfaces 24 and 25 on the free end of the block B may be correspondingly varied as to number. Also it will be understood that in place of two wedging portions 46 and 47 a greater number of such wedging portions might be provided on the wedge or a single wedging portion utilized, and in such event the underside of the lip of the clamp plate would be provided with more than two inclined surfaces or with a single inclined surface as the case might be.

As previously stated, the wedge embodying the invention can be used with great utility in a rail brace construction employing the usual hold-down arrangement wherein the action of the hold-down bolts is simply a vertical hold-down action.

In Figs. 6 to 10 inclusive a modified form of rail brace construction embodying the invention is disclosed. The difference between this modified form of construction and the first described form of construction resides in the wedge and in the arrangement of the surfaces on the block B' and

clamp plate 35 that cooperate with the wedging surfaces of the wedge. Accordingly it will not be necessary to repeat herein the description of those portions of the construction which are identical with the previously described construction and the same reference characters are employed in Figs. 6, 7 and 8 to indicate the corresponding parts as are employed in the previous views.

The free end of the portion 22 of the block B' 10 of the modified construction is provided with oppositely inclined surfaces 48 and 49 that serve the function of the surfaces 24 and 25 of the previously described form. The surfaces 48 and 49 are inclined inwardly of the block B' and 15 away from the adjacent straight side of the fixed abutment member 18 and their inner ends are separated by a recess 50 formed in the free edge of the portion 22 of the block B'.

In the modified construction, in place of using 20 a single wedge member provided with a plurality of wedging surfaces a pair of separate wedge members 51 and 52 is employed and which separate wedge members are provided on their sides with wedging surfaces 53 and 54, respectively, 25 that cooperate with the inclined wedging surfaces 48 and 49 respectively. The wedge members 51 and 52 are positioned between the free end of the portion 22 of the block B' and the adjacent straight side of the back stop 18 and beneath the 30 lip of the clamp plate 35, with the large ends of the wedge members located inwardly and adjacent to each other, wherefore the wedging action of the wedge members is increased by the movement of the members outwardly away from each other and toward the opposite longitudinal sides of the base plate 16.

In order to produce such movement automatically during the use of the rail brace in trackage, the wedge members 51 and 52 are provided with 40 inclined upper surfaces 55 and 56, such surfaces being inclined upwardly from the large or inner ends of the wedge members toward the smaller or outer ends thereof. The inclined surfaces 55 and 56 cooperate with similarly inclined surfaces 45 57 and 58 formed on the underside of the lip of the clamp plate 35 and having their inner ends separated by a recess 59 formed on the underside of said lip.

It will be seen that when the rail brace of Figs. 50 6 to 10 inclusive is installed and the surfaces 57 and 58 on the underside of the lip of the clamp plate 35 are pressing on the upper surfaces 55 and 56 of the wedge members 51 and 52, a reaction occurs that tends to move said wedge members outwardly and away from each other in a 55 tightening direction. Under the vibrations, jars and shocks produced by trains passing along the rail this tendency is augmented and the wedge members actually move in the self-tightening direction and thus are maintained in a position 60 at all times wherein the wedge members function to wedge the block B' toward the rail into proper clamping and bracing relationship with respect to the rail. In other words, the wedge members 65 51 and 52 are self-tightening similarly to the single wedge member 40 of the previously described form and the construction shown in Figs. 6 to 10 possesses all the advantages enumerated for the previously described construction.

70 Further it will be noted that not only is it unnecessary to drive the wedge members 51 and 52 into operative position but that actually it is impossible to do so and hence the danger of a workman attempting to drive the wedge members home is avoided. Also the wedge members

51 and 52 cannot possibly free themselves from assembled relationship in the brace construction since any outward movement of the wedge members acts to tighten the wedge members into their operative wedging relationship.

Although several embodiments of the invention have been illustrated and described herein it will be understood that the invention is susceptible of various modifications and adaptations within the scope of the appended claims.

Having thus described our invention, we claim:

1. A rail brace construction comprising, in combination, a base plate element adapted to be secured to a tie and to support the base of a rail, said base plate element being provided with a fixed stop adapted to be engaged by one of the rail base flanges and with a fixed abutment member spaced from said stop; a block element, and wedge means; said block element being provided with a portion adapted to engage the web of said rail and with a second portion extending outwardly therefrom and overlying said base plate element and adapted to be connected thereto by hold-down bolt means, and a lip part connected with and extending from said second portion and overlying said wedge means; said wedge means being interposed between said second portion and said abutment member with said wedge means, second portion and member having cooperating wedging surfaces and cooperating straight surfaces that cause said wedge means to urge said block element toward said rail; said wedge means, said base plate element and said lip part being provided with cooperating contacting surfaces including wedge tightening surfaces inclined to the horizontal in a direction to cause the force of the hold-down bolt means to react on said tightening surfaces and tend to urge the wedge means at all times, and particularly under the vibrations created by moving trains, to move in a direction to increase the wedging cooperation between said wedging surfaces.

2. A rail brace construction as defined in claim 1 and wherein said wedge means, said base plate element and said lip part are provided with cooperating contacting surfaces including a plurality of sets of wedge tightening surfaces inclined to the horizontal in a direction to cause the force of the hold-down bolt means to react on said tightening surfaces and tend to urge the wedge means at all times to move in a direction to increase the wedging cooperation between said wedging surfaces.

3. A rail brace construction as defined in claim 1 and wherein said wedge means, said base plate element and said lip part are provided with cooperating contacting surfaces including a plurality of sets of wedge tightening surfaces inclined to the horizontal in a direction to cause the force of the hold-down bolt means to react on said tightening surfaces and tend to urge the wedge means at all times to move in a direction to increase the wedging cooperation between said wedging surfaces, the said sets of wedge tightening surfaces being spaced apart longitudinally of each other.

4. A rail brace construction as defined in claim 1 and wherein said wedge means includes a wedge member having a wedging surface on one side thereof and an inclined wedge tightening surface on an adjacent side thereof.

5. A rail brace construction as defined in claim 1 and wherein said wedge means includes a plurality of separate wedge members.

6. A rail brace construction as defined in claim

1 and wherein said wedge means and said lip part are provided with cooperating contacting wedge tightening surfaces inclined to the horizontal in a direction to cause the force of the hold-down bolt means to react on said wedge means and urge the latter at all times to move in a direction to increase the wedging cooperation between said wedging surfaces.

7. A rail brace construction as defined in claim 10 1 and wherein said second portion of said block element and said wedge means are provided with cooperating wedging surfaces and said fixed abutment member and said wedge means are provided with cooperating straight surfaces.

8. A rail brace of the type described for use against a rail supported on a base plate and comprising a block having a rail engaging portion and a laterally extending portion adapted to overlie the base plate which supports the rail, said laterally extending portion being provided with means adapted to cooperate with hold-down bolts to connect the brace to the base plate, said laterally extending portion being provided with an end surface, wedge means cooperating with said end surface and adapted to cooperate with a fixed abutment carried by the base plate to wedge said block toward the rail, and a lip part connected with and extending from said laterally extending portion and overlying said wedge means, said lip part and said wedge means being provided with cooperating contacting wedge tightening surfaces inclined to the horizontal in a direction to react under the forces to which the brace is subjected in use to urge said wedge means automatically in a wedge tightening direction.

9. A rail brace as defined in claim 8 and wherein the end surface of the laterally extending portion is an inclined wedging surface that cooperates with an inclined wedging surface of said wedge means.

10. A rail brace as defined in claim 8 and wherein said lip part and said wedge means are provided with a plurality of pairs of cooperating contacting wedge tightening surfaces inclined to the horizontal in a direction to react under the forces to which the brace is subjected in use to urge said wedge means automatically in a wedge tightening direction.

11. A rail brace as defined in claim 8 and 50 wherein said lip part is integral with a clamp plate adapted to cooperate with the hold-down bolts that connect the brace to the base plate, said lip part on its underside and said wedge means on its upper side being provided with cooperating contacting wedge tightening surfaces inclined to the horizontal in a direction to react under the forces to which the brace is subjected in use to urge said wedge means in a wedge tightening direction.

12. A rail brace as defined in claim 11 and wherein the contacting surfaces on the underside of the lip part of said clamp plate and on the upper side of said wedge means are arranged in cooperating pairs spaced longitudinally of each other.

13. A rail brace construction as defined in claim 11 and wherein said wedge means comprises a plurality of separate wedge members.

14. A rail brace construction comprising, in combination, a base plate element adapted to be secured to a tie and to support the base of a rail, said element being provided with a fixed stop adapted to be engaged by one of the rail base flanges and with a fixed abutment member spaced from said stop; a block element provided with a

first portion adapted to engage the web of said rail and the downwardly sloping upper surface of one of the base flanges of the rails, said block element being provided with an integral second portion extending outwardly of said first portion and overlying said base plate element, a lip part connected with and extending from said second portion toward said abutment means; hold-down means interconnecting said base plate and block element and including hold-down bolts and cooperating engaging surfaces disposed to produce hold-down forces on said block element including a component force acting to urge said block element toward said rail and upwardly of the downwardly sloping surface of said one of the rail base flanges; and wedge means interposed between said second portion of said block element and said abutment member and overlying said lip part, with said wedge means, second portion and member having cooperating wedging surfaces and cooperating straight surfaces that cause said wedge means to urge said block element toward said rail; said wedge means, said base plate element and said lip part being provided with cooperating contacting surfaces including wedge tightening surfaces inclined to the horizontal in a direction to cause the force of the hold-down means to react on said wedge means and tend to urge the wedge means at all times to move in a direction to increase the wedging cooperation between said wedging surfaces.

15. A rail brace construction as defined in claim 14 and wherein the axes of said hold-down bolts are disposed at an inclination to the perpendicular and substantially at right angles to the downwardly sloping upper surface of said one of the rail base flanges, while said cooperating engaging surfaces of the hold-down means are downwardly inclined in the same direction as said upper surface of said one base flange of the 40 rail but disposed at an angle thereto.

16. A rail brace as defined in claim 14 and wherein said second portion of said block element and said wedge means have cooperating wedging surfaces while said abutment member and said wedge means have cooperating straight surfaces.

17. A rail brace as defined in claim 14 and wherein the hold-down means includes a clamp plate cooperating with the hold-down bolts and provided with one of the said cooperating engaging surfaces, said lip part overlying said wedge means being integral with said clamp plate, the

underside of said lip part and the upper side of said wedge means being provided with the said cooperating contacting wedge tightening surfaces.

18. In a rail brace of the type used against a rail supported on a base plate and including a block having a rail engaging portion and an integral portion extending laterally therefrom and adapted to overlie the base plate which supports the rail and provided with means adapted to cooperate with hold-down bolts, wedge means for urging the block toward the rail, and a lip part connected with and extending from said integral portion and overlying said wedge means; the improvement which comprises providing said wedge means on a side thereof disposed at substantially ninety degrees to its wedging side with an upwardly inclined wedge tightening surface and providing said lip part with a complementary adjacent surface cooperating with said wedge tightening surface of said wedge means.

19. A wedge for a rail brace comprising a member having on opposite sides thereof a wedging surface and a straight surface, respectively, and provided on another side thereof with a surface inclined upwardly in a direction toward the low end of said wedging surface and adapted to cooperate with a complementary surface on a rail brace construction.

20. A wedge for a rail brace comprising an elongated member having a straight side and an opposite side provided with a plurality of longitudinally spaced similar wedging surfaces; said member having another side provided with a plurality of longitudinally spaced similar surfaces inclined upwardly in a direction toward the low ends of said wedging surfaces and adapted to cooperate with complementary surfaces on a rail brace construction.
